The ornamental design for combined stepper and simulated skiing exerciser, as shown and described.

DESCRIPTION

FIG. 1 is a perspective view of combined stepper and simulated skiing exerciser showing my new design in the stepper configuration;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof; and,

FIG. 8 is a perspective view thereof in the simulated skiing exerciser configuration.

FIG.1

FIG. 2

FIG. 3

FIG. 5

FIG. 4

FIG. 6

FIG. 7
